DESIGN FOR A WALL BRACKET

Freda Diamond, New York, N. Y., assignor to Syracuse Ornamental Co. Inc., Syracuse, N. Y., a corporation of New York

Application March 23, 1946, Serial No. 127,877

Term of patent 14 years

(Cl. D33—3)

To all whom it may concern:

Be it known that I, Freda Diamond, a citizen of the United States, residing in New York, in the county of New York and State of New York, have invented a new, original, and ornamental Design for a Wall Bracket, of which the following is a specification, reference being had to the accompanying drawing, forming a part thereof, wherein:

Fig. 1 is a perspective view, looking from a position forwardly to and above a wall bracket embodying my new design, and

Fig. 2 is a perspective view thereof while looking from a position forwardly of and beneath the same.

I claim:

The ornamental design for a wall bracket, substantially as shown.

FREDA DIAMOND.
